UNITED STATES PATENT OFFICE

SIMON MORRISON, OF NEW YORK, N. Y.

DESIGN FOR A VANITY CASE

Application filed October 3, 1929. Serial No. 32,919. Term of patent 14 years.

To all whom it may concern:

Be it known that I, SIMON MORRISON, a citizen of the United States, residing at 24 Mount Morris Park West, in the city of New York, county of Bronx, and State of New York, have invented a new, original, and ornamental Design for Vanity Case, of which the following is a specification, reference being had to the accompanying drawing, forming part thereof.

In the drawing:

Fig. 1 is a top plan view of a vanity case embodying my design;

Fig. 2 is a front edge view, and

Fig. 3 is a side edge view of the same.

I claim:

The ornamental design for a vanity case, as shown.

SIMON MORRISON.
